JACKET

Louis E. Dennis, Affton, Mo.

Application June 17, 1955, Serial No. 36,557

Term of patent 14 years

(Cl. D3—4)

The back of the jacket is conventional.

I claim:

The ornamental design for a jacket, as shown and described.
